UNITED STATES PATENT OFFICE.

CARL V. BULOW, OF BRIDGEPORT, CONNECTICUT.

JOINT.

1,391,364.

Specification of Letters Patent. Patented Sept. 20, 1921.

Application filed September 20, 1920. Serial No. 411,638.

To all whom it may concern:

Be it known that I, CARL V. BULOW, a subject of the King of Sweden, residing at Bridgeport, in the county of Fairfield and 5 State of Connecticut, have invented a new and useful Joint, of which the following is a specification.

- This invention has for its object to provide a novel and reliable joint of simple and 10 practical structure which is adapted to be easily and quickly manipulated when it is desired to connect members between which the joint is to be located, or to disconnect the members to break the joint.
- 15 With the above and other objects in view, the invention comprises the construction, arrangement and combination of parts as now to be fully described and hereinafter specifically claimed.
- 20 In the accompanying drawing forming a part of this specification,

Figure 1 is a perspective view of a key ring in which is incorporated the joint of the invention;

25 Fig. 2 is an elevational view of the two portions of the joint as when together, but not locked to each other;

Figs. 3 and 4 are perspective views of the two portions as when separated from 30 each other to break the joint;

Fig. 5 is an elevational view corresponding with Fig. 2, but showing the portions of the joint as when locked to each other; and

35 Fig. 6 is a sectional view on line 6—6 in Fig. 5, looking in the direction of the arrows.

Referring to Figs. 2 to 6, both inclusive, of the drawing, 10 denotes members which 40 are to be secured to each other, end to end. The members are shown as of circular cross-sectional configuration. It will be evident as the description proceeds that they may have any cross-sectional configuration. The 45 joint invented by me consists of two similar portions now to be fully described, one carried by each of members 10, which are adapted to interlock with each other and are provided with means whereby their interlocking 50 ing relation may be insured.

Projecting from an end of each of the members to be connected is a reduced extension 11 of circular cross-sectional configuration. The reduced extensions may be integral 55 with the members, or may be securely

fixed thereto. As shown more clearly in Figs. 3 and 4, each reduced extension is cut away to provide a depression 12 and a shoulder portion 13, the shoulder portion of each reduced extension being adapted to seat in 60 the depression of the other reduced extension and to fill the depression so that the members cannot be moved longitudinally with respect to each other. It is to be understood that the inventive idea in this regard is not limited to the particular configuration of depressions and shoulder portions disclosed in the drawing. The reduced extensions can be cut away in any desired manner to provide equivalent interlocking 65 means whereby the members cannot be moved longitudinally with respect to each other when the shoulder portions and depressions, respectively, are in engagement with each other. As will be apparent from 70 Figs. 2, 5 and 6, the reduced extensions are cut away to sufficient depths so that when put together, they will constitute a complete cylinder consisting of the whole of both of the reduced extensions. 75

As shown very clearly in the drawing, each reduced extension is provided at its attached end with a circumferential groove 14 adapted to rotatably receive an internal circumferential shoulder 15 of a tubular 85 member 16 which is adapted to freely turn on the reduced extension, but cannot be removed therefrom. As disclosed in Figs. 3 and 4, the tubular members are cut away to provide portions 17 adapted to engage each 90 other in such manner that when the shoulder portions and depressions of the reduced extensions are in engagement to form a perfect cylinder, the tubular members form one continuous tube completely inclosing the 95 cylinder of the reduced extensions and adapted to be turned thereon as a unit, as will be readily understood.

The method of manipulating the portions to make and break the joint will be obvious. 100 When it is desired to make the joint, each tubular member is arranged on its reduced extension as shown in Figs. 3 and 4. The portions are next moved against each other so that the shoulder portions engage the depressions to form a complete cylinder and the tubular members engage each other to form a complete tube inclosing the cylinder. The complete tube is then grasped and turned on the cylinder until it has reached 105 110

the position disclosed in Figs. 5 and 6. In this position of the parts the members cannot move longitudinally with respect to each other by reason of the location of the shoulder portions in the depressions, and they 5 cannot move laterally or sidewise with respect to each other for the reason that the continuous tube completely surrounds the cylinder of the reduced extensions, and that 10 any movement of the tubular members of the continuous tube from each other would be arrested by the reduced extensions, as will be clear from Fig. 6. When now it is desired to break the joint the continuous 15 tube is turned back to the positions of the tubular members on the reduced extensions as disclosed in Figs. 3 and 4, that is, to the line indicated by reference character A in Fig. 2. When the parts are in this position 20 the portions of the joint can be moved from each other, as is obvious. It will be evident that a spring or other mechanism can be incorporated in the joint to indicate the "breaking" position of the continuous tube 25 on the complete cylinder.

I have shown in Fig. 1 one application of the joint of the invention. B denotes a swivel joint connecting the two halves, denoted by C, of a key ring. D denotes generally 30 the joint constituting the subject-matter of the invention as fully shown and described. It is to be understood, however, that the joint is capable of use to connect any two members end to end.

35 It should be noted that while the continuous tube formed by the tubular rotatable members may be a continuation of both of the members joined to each other, as shown, this is not essential. Each member to be 40 joined can be of any cross-sectional configuration, and two members to be joined can be of different cross-sectional configurations. The grooves which swivel the tubular members onto the members to be connected, must, however, be circular grooves 45 to allow the continuous tube to rotate on the cylinder.

It should further be noted that while the continuous tube is adapted to freely turn 50 on the cylinder, it is sufficiently tight on said cylinder to preclude the possibility of accidental turning of the tubular members to breaking position when the joint is made.

While I have shown and described one 55 specific embodiment of the invention, it is to be understood that such changes in details of construction and arrangement of parts may be made as fall within the scope of the invention as claimed.

60 What I desire to claim is:

1. A joint consisting of a pair of interlocking members and a pair of cut-away tubular members rotatably mounted thereon, said tubular members capable of rotating on 65 said interlocking members as a unit to be

positioned so that said interlocking members can be either moved from or held to each other.

2. A joint consisting of a pair of interlocking members each having a circular 70 groove and a pair of cut-away tubular members each provided with an internal circumferential shoulder adapted to rest in said circular groove, said tubular members capable of rotating on said interlocking members as a unit to be positioned so that said interlocking members can be either moved from or held to each other. 75

3. A joint consisting of a pair of interlocking members attached to a pair of members to be connected and each provided with a circular groove, a pair of cut-away tubular members, and an internal circumferential shoulder at one end of each of said tubular members, said internal shoulders adapted to 80 rest in said circular grooves to rotatably secure said tubular members on said interlocking members, whereby said interlocking members can be capable of moving laterally with respect to each other or can be held 85 against lateral movements.

4. A joint consisting of a pair of interlocking members adapted to be placed together to form a complete cylinder and each provided with a groove, and a pair of tubular members provided with means entering the grooves whereby the tubular members are rotatably supported on the interlocking members and completely inclose the same in such manner that the interlocking 100 members can be moved from each other or can be held against lateral movements with respect to each other. 95

5. A joint consisting of a pair of interlocking members each provided with a 105 shoulder portion and a depression, the shoulder portion of each of said interlocking members adapted to rest in the depression of the other of said interlocking members to preclude longitudinal movement of said 110 interlocking members with respect to each other, and a cut-away tubular member rotatably mounted upon each of said interlocking members, said cut-away tubular members adapted to completely inclose said 115 interlocking members when said shoulder portions and depressions are in engagement with each other, whereby lateral movement of said interlocking members with respect to each other may be prevented. 120

6. A joint consisting of a pair of interlocking members each provided with a shoulder portion and a depression, the shoulder portion of each of said interlocking members adapted to rest in the depression 125 of the other of said interlocking members to preclude longitudinal movement of said interlocking members with respect to each other, and a cut-away tubular member adapted to be rotated upon each of said in- 130

terlocking members, said cut-away tubular members adapted to together completely inclose said interlocking members when said shoulder portions and depressions are in engagement with each other, whereby said interlocking members may be precluded from having lateral movement with respect to each other.

7. A joint consisting of a pair of interlocking members which when interlocked form a cylinder, and a continuous tube inclosing said cylinder, said continuous tube consisting of a pair of tubular members hav-

ing cut-away portions which are rotatably mounted on said interlocking members, and 15 being capable of rotating on said complete cylinder as a unit, whereby said continuous tube can be positioned so that said interlocking members can be moved from each other, or can be positioned to hold said interlocking members to each other, as fully hereinbefore described.

Signed at Bridgeport, in the county of Fairfield, and State of Connecticut, this 15th day of September, 1920.

CARL V. BULOW.
